DEEP WELL PUMP

Thaddeus S. Harris, Waverly, Ill.

Application August 4, 1938, Serial No. 223,005

8 Claims. (Cl. 103—5)

The object of this invention is to provide a deep well pump in which the pump head need not be set directly over the well, and a pump in which the usual cylinder in the well, and the pump rod to operate it, are eliminated. These two features constitute the chief advantages of the construction here shown and described.

The main operating principle of this pump is that of using a jet of water, at comparatively high pressure, delivered at the small end of a Venturi tube, which jet draws in water around the tip and delivers it against considerable pressure. Other features are also introduced, as herein described, to provide balanced and efficient operation and automatic repriming.

Referring to the drawing, this single figure shows a vertical section of the complete pumping plant and storage tank. 1 is a standard type double acting force pump, which may be operated by the lever 2. The discharge chamber 3 has two pipes 4 and 4' connected thereto. Pipe 4 extends to the well 5, where it is connected to the well units as herein described. Pipe 4' is connected to the Venturi tube unit 8, which unit is connected at its upper end, by pipe 9, to storage tank 10. A check valve 11 is connected into the pipe 9.

The Venturi tube unit 8 has an adjustable needle valve 12 for controlling the flow through the jet 12'.

From the intake port 1' of the pump, the suction pipe passage 13, 13' extends to the well 5, where it is connected to the top of Venturi tube 6. Connected into this suction passage is a diaphragm chamber 14 with the diaphragm 15. The lower side of diaphragm 15 is subject to atmospheric pressure. A valve rod 16 is fixed to the center of diaphragm 15 and carries valve 17 which controls port 18. Port 18 is connected by a passage 19' to the lower portion of Venturi tube 8, a check valve 19 being connected into the passage. The valve 17 is by-passed by the small air port 17'. A spring 16' operates to hold valve 17 open, when pump is not operating.

An automatic priming valve is comprised of the diaphragm chamber 20 with diaphragm 21, the left side of which is open to atmospheric pressure. Diaphragm 21 carries valve rod 22, on which is mounted a valve 23, controlling port 24. Port 24 is connected by pipe 25 to tank 10. A spring 21 holds valve 23 closed, normally. Diaphragm chamber 20 is connected by pipe 26 to a port 26' in the side of pipe passage 13, 13'.

The jet 6' in Venturi tube 6 is connected by pipe 27 to pipe 4. An air port 28, in the base of Venturi tube 6, is connected to the top portion of

the well by a pipe 29, a check valve 30 being connected into this passage. A hand valve 31 controls pipe 29.

The top of Venturi tube 7 is connected to the bottom of Venturi tube 6 by pipe 7. The jet 32 is connected by a pipe 32' to pipe 4. There is a passage 33 from unit 7 to the water of the well, a check valve 34 being connected into the passage.

When pump 1 is operated it develops a high degree of vacuum in pipe 13, 13', causing valve 17 to close. If the water level in the well should be lower than about thirty feet below the pump head, then no water can be lifted by mere suction. But the high degree of vacuum causes valve 23 to open so that water from tank 10 may flow through pipes 25 and 26 to pipe 13'. The pump then builds up pressure in the discharge chamber 3, so that jets 6', 32 start operating. Water is then lifted from the well through pipe 13', in such quantities that the partial vacuum becomes greatly reduced in pipe 13' so that valve 23 closes. In the meantime water is also being discharged through jet 12', passing to tank 10, valve 19 remaining closed. Whenever the partial vacuum in pipe 13, 13' falls to only about five pounds below atmospheric pressure the valve 17 is caused to open by spring 16' so that water is drawn into the base of Venturi tube 12', directly from pipe 13, without having passed through the pump. The amount of water discharged to the tank then becomes increased because of higher level of the water in the well. Also the operation of valve 17 insures that at very low water levels there will be a full flow of water to the pump, due to valve 17 closing when high degrees of vacuum are produced in pipe 13.

If hand valve 31 is opened, then small quantities of air are drawn into the lower portion of Venturi tube 6, filling the column of water with air bubbles, thereby rendering it lighter so that water can be lifted from greater depths. This air collects in diaphragm chamber 14 and passes through air port 17' directly to the tank 10, and so does not interfere with the operation of the pump.

In the operation of jet 12', the needle valve 12, besides controlling the amount of flow, also gives the flow a divergent character, which greatly assists in creating a suction force at the small end of the Venturi tube.

I claim as new:

1. In a deep well pump unit, the combination of a suction type force pump, a pressure reducing jet connected into the discharge pipe therefrom, said jet being disposed at the small end of a Venturi tube, a suction passage from said pump, ex-

tending to a well, a boosting unit in the well, connected to said suction passage, said boosting unit comprising a Venturi tube with jet at its lower end, said jet being connected by a closed passage 5 to the discharge chamber from said pump, a bypass passage from said suction passage to the small end of said Venturi tube which is connected into the discharge passage, a check valve in said by-pass passage and also an automatic valve assembly 10 in said passage, said automatic valve assembly comprising a diaphragm chamber, a diaphragm across said chamber, said diaphragm being operably connected to said valve, one side of said diaphragm being exposed to atmospheric 15 pressure while the other side is exposed to the pressure within the suction passage and a spring disposed to hold said automatic valve open, normally.

2. In the combination of a pump, storage tank 20 and jet booster unit means for automatically repriming said pump, said means comprising the combination of a suction type force pump, a storage tank connected to the discharge passage from said pump, a suction passage extending from said 25 pump to a supply reservoir, a diaphragm chamber, a diaphragm across said chamber, one side of said diaphragm chamber being closed and connected to said suction passage by a closed pipe, a port in this side of said chamber, said port being 30 connected to said tank by a closed passage, a valve in said port, said valve being operably connected to said diaphragm and a spring disposed to hold said valve closed, normally.

3. In a deep well pumping plant, the combination 35 of a suction type pump, a supply reservoir, a discharge passage from said pump, a pressure reducing valve in said discharge passage, a suction supply passage from said pump to said supply reservoir, a jet booster unit in said supply passage, a jet inlet to said jet booster unit, a passage from said jet inlet of said booster unit to the discharge passage from said pump and a by-pass passage from said supply passage to said pressure reducing valve.

45 4. In a deep well pumping unit, the combination of a suction type pump and a pressure reducing valve connected into the discharge passage from said pump, said valve comprising an intake chamber, said chamber being connected to the discharge passage from said pump, a discharge port from said chamber, said port being disposed to discharge into the small end of a Venturi tube, said port having disposed in it a conical shaped 50 needle type valve, a second intake chamber, said chamber being disposed adjacent to said first chamber and around said discharge port and needle valve and a port from said second intake chamber, said port being connected by a closed passage to the intake supply passage to said 55 pump.

60 5. In a deep well pumping plant the combination of a suction type pump, a discharge passage from said pump, an intake supply passage to said pump from a source of supply, a jet booster unit in said supply passage, a passage from said jet unit to said discharge passage, an air port into said booster jet unit, a passage from said air port to the top of the well and a control valve in said 65 passage.

6. In a deep well pumping plant, a suction type force pump, a storage tank, a discharge passage from said pump to said tank, a pressure reducing valve connected into said discharge passage, a suction passage from said pump, a booster unit connected into said suction passage, said boosting unit comprising a cone shaped tube, the large end of said tube being connected to said passage, a jet opening into the small end of said tube, said jet being connected by a closed passage to the discharge chamber of said pump, a passage connecting said small end of tube to the water of a well, a valve in said passage, a by-pass passage from said storage tank to the intake chamber of said pump, an automatically controlled valve in said by-pass passage, a diaphragm chamber, a diaphragm across said chamber, said diaphragm being operably connected to said valve, one side of said diaphragm being subject to a pressure which exceeds the normal operating pressure within the passage, and a spring disposed against the opposite side of said diaphragm.

7. In a deep well pumping plant the combination of a suction type force pump, a storage tank, a discharge passage from said pump to said tank, a pressure reducing valve connected into said passage, a suction passage extending from said pump to the water of a well, a check valve in said passage, a booster unit, said unit comprising a cone shaped tube connected into said suction passage with its large end connected to said pump by said suction passage, a jet disposed to discharge into the small end of said tube, said jet being connected by a closed passage to the discharge chamber of said pump, a by-pass passage from the intake passage of said pump to said storage tank, an automatically controlled valve in said by-pass passage, a yieldable section in the wall of said passage, said section being operably connected to said valve, the outer side of said section of wall being subject to a pressure which is greater than the normal operating pressure within the passage and a spring disposed against the inner side of said section of wall.

8. In a deep well pumping plant, the combination of a suction type force pump, a storage tank, a discharge passage from said pump to said tank, a pressure reducing valve connected into said passage, a suction passage extending from said pump to the water of a well, a booster unit, said booster unit comprising a cone shaped tube connected into said suction passage with its large end connected to said pump, a jet disposed to discharge into the small end of said tube, said jet being connected by a closed passage to the discharge chamber of said pump, a by-pass passage from the intake passage of said pump to said storage tank, an automatically controlled valve connected into said by-pass passage, a yieldable section in the wall of said passage, said yieldable section being operably connected to said valve, the outer side of said yieldable wall section being subject to a pressure which is materially different from the normal operating pressure within that section of the by-pass passage which is between said valve and said pump intake passage, and a spring disposed to move said wall section in cooperation with its pressure differentials.

THADDEUS S. HARRIS.
